APPARATUS FOR TREATING MATERIALS

William L. Wettlaufer, Buffalo, N. Y., assignor to
The W. S. Tyler Company, Cleveland, Ohio, a
corporation of Ohio

Application January 8, 1934, Serial No. 705,724

4 Claims. (Cl. 209—44)

This invention relates to certain new and useful improvements in an apparatus for treating and conveying materials of various kinds and for recovering certain desired portions or elements of the material-content.

One of its objects is the provision of an efficient apparatus of this character which is so designed as to provide a unitary structure including a screening unit and a conveying means onto which the fines are deposited, and which is also designed for use in separating and reclaiming processes, whereby all or part of the material is conveyed to a predetermined discharge point.

Another object of the invention is to provide simple, reliable and efficient means for imparting a positive gyratory movement to the screen frame as well as a positive feed to the conveying means.

Other features of the invention reside in the construction and arrangement of parts herein-after described and particularly pointed out in the appended claims.

In the accompanying drawings:—

Figure 1 is a perspective view of the apparatus embodying my invention. Figure 2 is a central longitudinal section thereof. Figure 3 is a side view of the apparatus showing the means for driving the conveyor from the main operating shaft of the machine. Figure 4 is a cross section taken substantially in the plane of line 4—4, Figure 2. Figure 5 is a central longitudinal section similar to Figure 2 showing a modification of the invention. Figure 6 is a perspective view of the conveyor shown in Figure 5.

Similar characters of reference indicate corresponding parts throughout the several views.

In the preferred embodiment of the invention shown in the drawings, the same consists of a gyrating body or live frame consisting of side plates 10, 10 carrying a plurality of screen decks 11 supported between the side plates. In the drawings, two of such screens are shown, the upper one being of a coarse mesh and the lower one of a fine mesh. Below the screening surfaces 45 to receive the material passed through the same, is a conveyor which is by preference in the form of an endless belt 12 extending practically the full width of the space between the side plates and passing at its ends around drums 13 suitably journalled in bearings 14 applied to the side plates. This screening and conveying unit or assembly is supported for a rotating or gyratory movement upon a suitable stationary frame structure 15 which may consist of I-beams, as shown, or may 55 be of any other suitable construction.

The live frame, including the screens 11 and conveyor 12, is balanced or supported for rotating vibratory movement midway of its ends on a rotary transverse shaft 16 journaled at its ends in suitable bearings 17 supported on the main frame 15 and extending through the side walls or plates 10 of the live frame at substantially its center of gravity. This shaft constitutes the drive shaft of the machine and imparts to the live frame a positive circular or gyrating movement, and to this end the shaft has eccentric portions 18 thereon which engage suitable bearings arranged with housings 19 applied to the side plates 10. Mounted on the shaft 16 between the live frame 10 and the supporting frame 15 are counter-balanced wheels 20. At one end, the operating shaft is provided with a pulley 21 which may be connected by a belt, not shown, with an electric motor or other source of power.

Adjacent its opposite ends, the live frame is resiliently supported upon compression springs 22 or like elements which may be arranged within suitable housings 23 applied to the outer sides of the side plates 10 and which are seated at their lower ends on supporting bars 24 secured to the frame-beams 15, the springs being disposed in substantially an upright position to yieldingly sustain the ends of the live frame.

The conveyor belt 12 is driven at a comparatively slow speed from the operating shaft 16 of the machine preferably by the following means:

Applied to one end of the operating shaft 16 is an eccentric pulley 25 which is so mounted thereon as to be in exact synchronism with the gyrations or oscillations of the screen-body and to this end an eccentric 25a is applied to said shaft about which the pulley is fitted. The bore of this pulley is of such eccentricity to its periphery that it exactly corresponds in magnitude and direction with the gyrating body actuating eccentric 18 of the driving shaft. This pulley is connected by a crossed belt 26 with a somewhat larger pulley 27 mounted on a shaft 28 suitably journaled in a housing 29 mounted on brackets 30 secured to the outer side of the adjoining side plates 10 of the machine. Arranged within this housing is a pinion 31 secured to the shaft 28 and meshing with a gear 32 fixed to a shaft 33 journaled substantially centrally of the housing. Said shaft 33 extends rearwardly through the housing 29 and fixed thereon is a pulley 34 about which one end of an endless belt 35 passes, the other end of the latter passing around a somewhat larger pulley 36 secured to a shaft 37 pro-

jecting from the adjoining end of the conveyor drum 13. By this motion-transmitting means, the conveyor belt 12 is moved at a comparatively slow speed while the live frame of the machine 5 bearing the conveyor and the screens 11 is gyrated at a comparatively high speed.

The belt 12 is preferably made of rubber or like material and its upper stretch between the drums 13 is supported on guide rolls 38.

10 In the modified form of the invention shown in Figures 5 and 6, the conveyor belt 39 is driven from the drive shaft 16 of the machine in the same manner as heretofore described. On its surface, however, it is provided with projecting 15 ribs or rifles 40 which are substantially V-shaped and which function to catch or intercept and retain the heavier particles from the materials passed through the screens 11, while the lighter particles pass downwardly from the gyrating of 20 the body 10 over the inclined moving belt into a suitable container provided for receiving them. The heavier particles move with the belt and are discharged at the opposite end of the belt, dropping therefrom by gravity into a suitable 25 container provided therefor.

I claim as my invention:—

1. In a screening apparatus, the combination of a frame mounted for gyratory movement and 30 provided with vertically disposed side walls, a shaft extending transversely of said frame centrally thereof, means on said shaft for imparting gyratory movement to said frame, a screen extending between said side walls above said shaft, spaced shafts extending between said side 35 walls below said first named shaft, and a conveyor belt trained about said second named shafts.

2. In a screening apparatus, the combination of a frame mounted for gyratory movement and provided with vertically disposed side walls, a shaft extending transversely of said frame centrally thereof, means on said shaft for imparting 5 gyratory movement to said frame, a screen extending between said side walls above said shaft, spaced shafts extending between said side walls below said first named shaft, and a conveyor belt trained about said second named shafts, said 10 conveyor belt provided with transversely extending ribs on its outer surface.

3. In a screening apparatus, the combination of a frame mounted for gyratory movement and provided with vertically disposed side walls, a 15 shaft extending transversely of said frame centrally thereof, means on said shaft for imparting gyratory movement to said frame, a plurality of vertically spaced screens extending between said side walls above said shaft, spaced shafts extending 20 between said side walls below said first named shaft, and a conveyor belt trained about said second named shafts.

4. In a screening apparatus, the combination of a frame mounted for gyratory movement and 25 provided with vertically disposed side walls, a shaft extending transversely of said frame centrally thereof, means on said shaft for imparting gyratory movement to said frame, a screen extending between said side walls above said shaft, spaced shafts extending between said side walls below said first named shaft, a conveyor belt trained about said second named shafts, and 30 means for driving said second named shafts from said first named shaft.

35 WILLIAM L. WETTLAUFER.
